APPARATUS FOR TREATING THE DEFECTIVE SURFACE METAL OF BILLETS OR THE LIKE

Augustus B. Kinzel, Douglaston, Long Island, N. Y., assignor, by mesne assignments, to Union Carbide and Carbon Corporation, a corporation of New York

Original application July 29, 1932, Serial No. 625,637. Divided and this application January 2, 1936, Serial No. 57,167

11 Claims. (Cl. 29—33)

This invention relates to apparatus for treating metallic bodies to eliminate surface defects, such as cracks or defectively bonded metal or abrupt irregularities of contour, and is a division 5 of my application Serial No. 625,637, filed July 29, 1932.

The present apparatus is particularly useful in the manufacture of steel. In this art the steel, first in the form of ingots, then blooms and then billets, is successively rolled at a high temperature. The working of the metal in any of these rolling steps often causes the surface of the metal to crack and form crevices known as snakes. The walls of these cracks become coated with oxides which prevent them from being welded together during the further rolling of the metal. Frequently, the defects, such as cracks and poorly bonded metal, are rolled into the body of the metal and become concealed during the rolling 20 operations. Also, when metal containing such defects is rolled, the defects increase in length in proportion to the reduction in area of cross-section of the metal object being rolled. Therefore, whenever such cracks occur in the metal it is necessary that they be eliminated before the metal is further rolled. It is also necessary that, upon eliminating the cracks or poorly bonded metal, the surface of the metal be left free from 25 abrupt irregularities of contour. That is, the abruptness of the slope of the sides of the elevations or depressions must not be so great that the oxide coated sides will be folded over on each other when rolled out and produce folds of oxides within the metal when further rolled.

Heretofore, the defective surfaces of blooms or billets have been prepared for subsequent rolling operations by cutting out the surface portions which contribute to the production of defects in the rolled or finished product. The removal of 40 the surface portions has been effected by mechanical methods, such as chipping or milling, and more recently by the use of a highly oxidizing stream of gas. Before the metal is operated upon by any of the prior methods mentioned 45 herein, the hot metal is allowed to cool to a comparatively low temperature to allow the inspectors to get close enough to the metal to detect and mark the undesirable metal portions to be removed, and to allow the metal removing operators to get close enough to operate upon the metal. During this cooling period time and heat energy are lost, as well as the time consumed during the reheating of the metal for subsequent 50 rolling.

Removing surface metal by milling and chip-

ping is very laborious and it consumes a great amount of time. While the removal of undesirable metal portions by the use of the oxidizing gas stream is less laborious and quicker than milling or chipping, it, like the prior methods, 5 cuts away substantial portions of the metal which is a waste. The loss of metal is due in part to the fact that it is necessary to cut out wide gouges to provide depressions having sides with slopes within the necessary minimum degree required 10 to prevent the sides of the depression from being folded over when rolled.

Therefore, one of the objects of this invention is to provide apparatus which will conserve time, labor, heat, and metal in eliminating surface defects from metallic bodies to prepare the surface of the metal for subsequent metal working processes.

Another object of this invention is to provide apparatus which will convert the surface of a 20 metallic body into a relatively smooth homogeneous mass firmly bonded to the body metal and substantially free from oxide inclusions.

Another object of this invention is to provide apparatus which will eliminate the necessity for 25 inspecting the surface of the metal for defects.

In accordance with this invention apparatus is provided to melt defective portions of the surface to the depth of the defective metal and thereby eliminate the oxide from the surfaces of 30 the cracks and the poorly bonded metal so that, upon solidifying, the surface will be welded together in a smooth homogeneous mass to the body metal. Preferably, the surface is melted with one or more electric arcs which may be 35 applied to the defective portion only, or to the entire surface of the metal. The arcs may be applied to the surface while the body of the metal is cold or immediately after it has been hot worked. In some instances it may be desirable 40 to subject the surface of the metal to the heat of the electric arc immediately after it has passed through the hot rolling operation for the purpose of conserving the heat in the metal at that point and to save the time and heat required to 45 heat the metal up for subsequent hot working operations. In such a case the metal is not inspected for defects and the entire surface of the metal is treated with a plurality of arcs.

The above and other objects and advantages of the present invention will become apparent from the following description and accompanying drawings, in which:

Fig. I is an isometric view of an apparatus 55

operating upon the surface of a bloom or billet; and

Fig. II is a modified detail of the apparatus shown in Fig. I; and

5 Fig. III is a diagrammatic view illustrating the location of the apparatus shown in Fig. I when arranged between two roll stands for treating the surfaces of billets during their movement between rolling operations.

10 As shown in Fig. I, the billet 1 to be treated is supported on rolls 2 as it is passed through a main stationary frame 3 which supports a plurality of carbon electrodes 4. An arc is drawn between one end of each of the electrodes and the 15 metal surface to be treated. Each of the arcs is struck and regulated automatically by any of the suitable well known automatic arc striking and electrode feeding devices. For clearness the electric circuit and a device 5 for regulating only 20 one of the arcs is shown diagrammatically.

In the circuit shown a generator 6 provides a source of current for the arcs. Preferably the positive side of the generator 6 is connected to the billet 1 and the negative side is connected to each of the electrodes 4. Each of the electrodes is held by an electrode holder 7. The holder 7 is actuated to strike and regulate the arc in the usual manner by a plunger 8. The plunger 8 is actuated by a solenoid 9 in series with the arc circuit. However, other suitable means for striking and regulating the arc may be employed.

The electrodes 4 are arranged in batteries in refractory insulative blocks 10 which are secured in slidable frames 11, 12, 13, and 14. Each of the 35 electrodes 4 is slidably guided in bores 15 in the blocks. The electrodes are arranged in rows and are staggered in relation to each other so that the arcs will play upon different portions of the billet 1 as it passes through the main frame 3. 40 The number of arcs may be varied as the conditions may require.

There may be as many batteries of electrodes as are required to play the arcs on all of the sides of the metal whose surface is treated. As shown, 45 the billet 1 has four sides and a battery of electrodes is provided for each side. As the billet passes through the frame 3 in the direction of the arrow A the electrode blocks 10 may be held stationary so that the travel of the arcs along 50 the surface of the work will be a straight line. In such a case the apparatus hereinafter described may be eliminated.

In order to cover the surface of each side of the billet more effectively the batteries of electrodes are given a movement transverse to the movement of the billet 1 as it passes through the main frame 3. For this purpose each slidable frame 11, 12, 13, and 14, in which the electrode blocks 10 are mounted, is provided with grooves 60 16 in opposite edges thereof which receive lands 17 on the main frame 3. The electrodes mounted in the top slidable frame 11 and in the near side slidable frame 12 are given the transverse movement by the rotation of a cam 18 keyed to a shaft 19 65 journaled in the upper near corner 20 of the main stationary frame 3. When the cam 18 is rotated, the high point 21 of the cam moves the slidable frames 11 and 12 on the lands 17 in the stationary frame 3 away from the cam shaft 19 70 and transversely of the movement of the billet 1. The slidable frames 11 and 12 are given a return transverse movement by springs 22 and 23 compressed between the stationary frame 3 and each 75 of the end edges of the slidable frames most distant from the cam 18. The springs 22 and 23

are maintained in place by pins 24 which pass through the coil of the springs. One end of each pin 24 is secured to the main frame 3 and the other end slides in a bore 25 in its respective slid-
able frame 11 or 12.

The bottom battery and the far side battery of electrodes are mounted in a manner similar to the other two batteries of electrodes in relation to a cam 26 and springs 27 (one of which is not shown) acting in opposition to the cam 26 on the edges of the slidable frames most distant from the cam for giving the electrodes 4 a transverse movement.

A bevel gear 28 is keyed to each of the cam shafts 19 and 29. The gears 28 on the cam shafts 15 are geared together by a horizontal shaft 30 and a vertical shaft 31, each having a gear 32 on one end meshing with one of the cam shaft gears 28 and gears 33 on the other ends meshing with each other. A bevel gear 34 keyed to a shaft 35 20 journaled in a bracket 36 on the main frame 3 meshes with a bevel gear 37 on the cam shaft 29. The cams 18 and 26 may be rotated through the train of gears described by a crank 38 on the shaft 35 journaled in the bracket 36 or by power 25 operated means or the like connected to the shaft 35.

In some cases it is preferred to protect the electric arcs from the surrounding air to prevent the surface of the metal from being oxidized by the action of the atmospheric oxygen in contact with the exposed arcs. For this purpose, as shown in Fig. II, the electrodes 4 are slidably mounted in bushings 39 which in turn are mounted in the blocks 10. A protective gas which is 35 inert in respect to the metal, such as hydrogen, is supplied through an inlet 40 to a cavity 41 in the bushings. The gas is discharged through an outlet 42 which is larger than the electrode 4 to allow the gas to envelop the electrode and the arc 40 drawn between the surface of the metal 1 and the electrode 4.

When, as hereinbefore described, billets are subjected to the surface conditioning treatment immediately after they have been hot-rolled and while they are still hot, the surface conditioning apparatus according to the invention, may be interposed between sections of the roller conveyor that carries the billet from one roll stand to the next as illustrated in Fig. III. The billets 1, 50 after being hot-rolled by the roll stand 43 in the customary manner, are conveyed and guided by the rollers 2 through the surface conditioning apparatus indicated at 44 which has been previously described in detail and which is here shown 55 enclosed within a protective covering supported by the frame 3. The billets 1, after the surface treatment, may pass from the apparatus 44 along the set of rollers 2 on the discharge side of the conditioning apparatus 44 to another stand of 60 rolls 45 which subject the treated billets to another hot rolling operation.

While a plurality of machine operated electrodes have been shown for treating the entire surfaces of a billet, it is to be understood that the 65 arcs may be applied to the defective portions of a surface only. It is also to be understood that other forms of apparatus may be used without departing from the scope of my invention as defined in the appended claims.

70 What is claimed is:

1. In apparatus for treating steel bodies such as ingots, blooms, billets and the like after they have been rolled to reduce their cross section and before they have cooled below the rolling 75

- temperature, the combination with a roller conveyor, of a supporting frame disposed adjacent to said conveyor, said conveyor being adapted to feed and move said steel bodies past said frame; and means carried by said frame for progressively subjecting successive surface portions of each body, during its movement past said frame, to a high temperature fault removing treatment to remove substantially all of the surface defects.
2. In apparatus for treating steel bodies such as ingots, blooms, billets and the like, the combination with a roller conveyor, of a supporting frame disposed adjacent to said conveyor, said conveyor being adapted to feed and move said steel bodies past said frame; and means carried by said frame for simultaneously subjecting a plurality of surfaces of each body, during its movement past said frame, to a high temperature fault removing treatment to remove substantially all of the surface defects in the surfaces of the bodies.
3. Apparatus for treating steel bodies such as ingots, blooms, billets, and the like to transform defective surface portions thereof into suitable condition for rolling, comprising the combination of means for applying localized heat having a temperature above the melting point of said body along zones extending completely across at least one surface of such body; and means for feeding the body longitudinally through the zone of localized heat to progressively treat successive surface portions of the body at a rate whereby the entire surface is substantially heated and said defects are substantially completely removed.
4. Apparatus for treating steel bodies such as ingots, blooms, billets, and the like to transform defective surface portions thereof into suitable condition for rolling, comprising the combination of means for applying localized heat to surface portions of such a body to superficially melt the surface and produce a homogeneous surface free from defects, said heating means comprising a plurality of carbon electrodes adapted to maintain an electric arc between the surface of the body and said electrodes, said arcs being staggered in respect to their relative movement with respect to the surface of the body; and means for feeding the body through the zone of localized heat to successively treat an entire surface of the body.
5. Apparatus for treating steel bodies such as ingots, blooms, billets, and the like to transform defective surface portions thereof into a suitable condition for rolling, comprising the combination of means for feeding such a body longitudinally through said apparatus; means for applying localized heat to surface portions of the body to superficially melt the surface and produce a homogeneous surface free from defects, said heating means comprising a plurality of carbon electrodes arranged in banks and adapted to maintain an electric arc between the surface of said bodies; and means for moving said electrodes parallel with said surface and transversely to the longitudinal movement of said bodies.
6. Apparatus for heating metallic bodies comprising banks of electrodes adapted to be disposed completely around the outer surfaces of such a body; means for maintaining an arc between each of said electrodes and the surfaces; means for moving said bodies longitudinally between said banks of electrodes; and means for simultaneously reciprocating said electrodes parallel with the surfaces and transversely of the longitudinal movement of the bodies.
7. In apparatus for treating steel bodies such as ingots, blooms, billets and the like after they have been rolled to reduce their cross section and before they have cooled below a rolling temperature, such steel bodies being rectangular in cross section, the combination with a conveyor; of a supporting frame disposed adjacent to said conveyor, said conveyor comprising spaced rollers adapted to support said bodies and move them in the direction of their length past said frame; and means carried by said frame for progressively subjecting successive surface portions of a side of each body, during its movement past said frame, to a high temperature fault removing treatment to remove substantially all of the surface defects of the side being treated.
8. Apparatus of the class described including in combination, mechanical means for successively hot working steel bodies, such as ingots, blooms, billets and the like; and thermal means operating on at least a portion of such a body between successive hot working operations and while the same is still at a hot working temperature for removing substantially all of the surface defects therefrom.
9. Metal rolling and surfacing apparatus comprising, in combination, mechanism for successively reducing the cross sectional area of steel bodies, such as ingots, blooms, billets and the like, by hot rolling; and means, including a device for applying high temperature heat to at least a portion of such a body between successive reductions, for removing substantially all of the surface defects from said portion while the same is at a hot rolling temperature.
10. Apparatus of the class described including in combination, means for successively reducing the cross sectional area of steel bodies such as ingots, blooms, billets and the like by hot working; and means for applying localized high temperature heat to surface portions of such a body between successive reductions and while the same is still at a hot working temperature to superficially melt the surface and produce a homogeneous surface free from defects.
11. Apparatus of the class described including in combination, spaced sets of rolls arranged to successively reduce the cross section of steel bodies such as ingots, blooms, billets or the like while they remain at substantially the same temperature; and means located between said sets of rolls for subjecting at least a portion of such a body to a high temperature fault removing treatment until surface defects are relatively completely removed therefrom.

AUGUSTUS B. KINZEL.
